UNITED STATES PATENT OFFICE.

THEODORE B. ROWELL, OF BEAVER DAM, WISCONSIN.

GRAIN-DRILL.

No. 879,495.

Specification of Letters Patent.

Patented Feb. 18, 1908.

Application filed July 27, 1907. Serial No. 385,908.

To all whom it may concern:

Be it known that I, THEODORE B. ROWELL, a citizen of the United States, and resident of Beaver Dam, in the county of Dodge and 5 State of Wisconsin, have invented certain new and useful Improvements in Grain-Drills; and I do hereby declare that the following is a full, clear, and exact description thereof.

10 The improvements consist in what is herein shown, described and claimed; the object of the invention being to simplify and cheapen the construction of grain-drills of the species having rotatory furrow-opening disks, as well as to provide for the utilization 15 of disk-supporting arms common to either long or short boots according as the drills are of high or low type, each boot being in detachable connection with a partly depending 20 rear portion of the corresponding arm having a scraper attached to its lower end.

Figure 1 of the accompanying drawings represents a side elevation of a grain-drill furrow-opening disk, its supporting-arm, a 25 boot in detachable connection with the arm and a scraper attached to said arm; Fig. 2, a horizontal section on the plane indicated by line 2—2 in Fig. 1; Fig. 3, a partly sectional side elevation of a fragment of the connected 30 arm and boot, the view being from the side opposite that from which Fig. 1 is taken, and Fig. 4, a rear elevation of the arm.

Referring by letter to the drawings, A indicates a fragment of a drag-bar riveted or 35 otherwise suitably fastened between parallel ribs b of a forward extension of an arm B, and the bearing-hub of an ordinary rotatory furrow-opening disk C engages an arbor-bolt c in connection with said arm. The arm B has 40 a partly depending rear portion B' that is concave at the back and of triangular form in horizontal section at the lower end, this lower end of said depending portion of the arm being forwardly extended and recessed at one 45 side. A disk-scraper D is riveted or otherwise fastened at its rear end in the lower end side recess of the depending portion of the aforesaid arm flush with the same. Bolted in the concavity of the partly depending portion B' of the arm B is a boot E, and this boot is provided with the usual rear eye-lug d for the attachment thereto of a suitable drag. The arm B is suitably bowed so that the discharge end of the boot will at all times register with the furrow opened by the disk C aforesaid.

As a matter of detail the boot is provided with a countersunk partly angular opening extending through a boss e of same. This boss engages a recess in the adjacent rear portion B' of the arm B, and central of said recess is an opening extending through a boss f of said rear portion of the arm. A partly angular bolt g extends through the openings in the boot and arm bosses and a clamping-nut h is run on the bolt against the arm-boss, the head of said bolt being within the countersink of the boot-opening.

From the foregoing it will be understood that the disk-scraper is an attachment of the 70 disk-supporting arm, and that this arm at the scraper-end of same is of such construction as to not interfere with a furrow cut by the disk. It will also be understood, that inasmuch as there is detachable connection 75 of the disk supporting arm and boot, the cost of replacing either in case one or the other is broken, will be less than were said arm and boot in one piece as is ordinarily the case, and furthermore the same arm can be utilized in 80 connection with either a long or short boot all depending as to whether the grain drill is of high or low-down type.

The arm may be a malleable or gray iron casting and the boot made of steel plate to 85 thus lighten the drill without sacrifice of strength. It also follows that a new disk-scraper may be readily substituted for one that is broken or worn out.

I claim:

1. The combination of an arm attachable to a drag-bar and having a partly depending rear portion concave at the back, a rotatory furrow-opening disk supported in connection with the arm, a disk-scraper attached to the 95 lower end of the rear portion of said arm, and a boot fastened in the concavity of said rear portion of the aforesaid arm.

2. The combination of an arm attachable to a drag-bar and having a partly depending 100 concave rear portion, a rotatory furrow-opening disk supported in connection with the arm and a boot detachably fastened to said rear portion of said arm in the concavity thereof.

3. The combination of an arm attachable to a drag-bar and having a rear concavity in which to detachably secure a boot, a rotatory furrow-opening disk in connection with the arm, and a disk-scraper also in connection 110 with said arm.

4. The combination of an arm attachable

to a drag-bar and having a partly depending rear portion concave at the back and provided with a recess and an opening central of the recess, a rotatory furrow-opening disk supported in connection with the arm, a boot fitting the concavity of the rear portion of said arm and having a countersunk partly angular opening extending through a boss engageable with the recess aforesaid, a partly angular bolt engaging the countersink and openings aforesaid, and a clamping nut run

on the bolt against said depending portion of the aforesaid arm.

In testimony that I claim the foregoing I have hereunto set my hand at Beaver Dam in 15 the county of Dodge and State of Wisconsin in the presence of two witnesses.

THEO. B. ROWELL.
